Harvey Lathen
ATTORNEY.

UNITED STATES PATENT OFFICE.

HARVEY MECOM, OF LIBERTY, TEXAS.

DRILLING APPARATUS.

Application filed July 22, 1926. Serial No. 124,142.

This invention relates to new and useful improvements in a drilling apparatus.

One object of the invention is to provide an apparatus of the character described comprising a rotatable stem, a drilling tool associated therewith, and a hammer associated with the stem and operable thereby and adapted to strike said tool with successive blows, as said stem is rotated to effect the abrasion or disintegration by said tool of the formation at the bottom of the bore.

Another object of the invention is to provide an apparatus of the character described in which the drilling tool is independently rotatable with respect to the stem but which may be clutched, or interlocked therewith so as to rotate, as a unit with said stem.

With the above and other objects in view this invention has particular relation to certain novel features of construction, operation and arrangement of parts, an example of which is given in this specification and illustrated in the accompanying drawings, wherein:

25 Figure 1 is a vertical sectional view of the lower end of the apparatus.

Figure 2 is a vertical sectional view of the upper end thereof.

30 Figure 3 is a transverse sectional view taken on the line 3—3 of Figure 2.

Figure 4 is a transverse sectional view taken on the line 4—4 of Figure 1.

Figure 5 shows a bottom view of the bit, and Figure 6 shows a fragmentary vertical sectional view of the apparatus.

Referring now more particularly to the drawings, wherein, like numerals of reference designate similar parts in each of the figures the numeral 1 designates a tubular drill stem which is adapted to be rotated by the usual rotary drilling machine. Attached to the lower end of this drill stem there is a tubular drill collar 2. There is a drilling tool embodying the bit 3, and the separable shank 4 which extends up into the drill collar 2. The collar 2 has an inside shoulder 5 and the shank of the drilling tool has a corresponding external shoulder 6. In assembling, the shank of the drilling tool is inserted down through the drill collar 2 and the bit of the drilling tool is then attached to said shank and the drill collar then attached to the stem 1. The shoulders 5 and 6 will prevent the detachment of the drilling tool from the drill collar. The shoulders 5 and 6 are formed with clutch jaws 5', 6' adapted

to engage to lock the drilling tool to rotate with the drill stem, and to be disengaged, to release said drilling tool so that the stem may rotate independent of it.

Incorporated into the drill stem 1 there is a special coupling 7 having a polygonal opening 8 therethrough and within the drill stem there is a vertically reciprocable hammer 9, having a polygonal section 10 which conforms in shape to and works through the opening 8, and forms an operative connection between the hammer and stem whereby the former is rotated by the latter.

Means have been provided for alternately 70 lifting the hammer and permitting the same to drop and strike the drilling tool. One form of such means, which may be employed will now be described:

The lower end of the hammer 9 abuts the 75 upper end of the shank 4 and these respective abutting ends have the oppositely disposed correspondingly inclined faces 11, 11 and 12, 12, which terminate in the oppositely arranged, vertically disposed abrupt 80 shoulders 13, 13 and 14, 14 respectively, the shoulders 13 facing in a direction the opposite of that of the shoulders 14.

In operation with the drill collar 2 resting on the bit 3 the clutch jaws of the 85 shoulders 5 and 6 will be disengaged and as the stem 1 is rotated the hammer 9 will rotate with it and the faces 11 will ride up on the faces 12 elevating the hammer 9, until the shoulders 13 pass the shoulders 14 and 90 the hammer 9 will then drop thus striking the upper end of the shank 4 in rapid succession and driving the bit 3 against the formation at the bottom of the bore and disintegrating the same. The sloping faces 11 95 striking the sloping faces 12 will impart a partial rotation to the drilling tool, so that as drilling proceeds the bit 3 will slowly turn and thus abrade away said formation, at the bottom of the bore.

If it be desired to rotate the drilling tool with the stem, the stem may be slightly elevated until said clutch jaws 5', 6' engage and the desired result thus accomplished. While the bit is thus rotated the weight of 105 the drilling tool and hammer 9 will rest on the bottom of the bore and this weight will be sufficient to cause the bit to disintegrate the formation at the bottom of the bore.

The hammer and drilling tool have water 110 courses 15 and 16 through which water may be supplied to flush away the bit cuttings

and the latter of which separates so as to discharge water on each side of the center of the bore being formed.

What I claim is:

- 5 A drilling apparatus including a stem, a tubular drill collar attached to the lower end of the stem, a drilling tool embodying a bit and a separable shank which extends up into the drill collar, said collar having an 10 inside shoulder and said shank having an opposing external shoulder above said internal shoulder, a coupling incorporating into the stem having a polygonal bearing therethrough, a vertical reciprocable ham-

mer within the stem having a polygonal section which works through said bearing and forms an operative connection between the hammer and stem, the lower end of the hammer and the upper end of the shank being provided with opposite correspondingly 20 inclined faces which terminate in oppositely arranged vertically disposed, abrupt shoulders, the shoulders of the hammer facing in a direction the opposite of that of the shoulders of the shank.

In testimony whereof I have signed my name to this specification.

HARVEY MECOM.
